CLAIM

The ornamental design for a hollow handle, as shown and described.

DESCRIPTION

FIG. 1 is an orthographic projection of a hollow handle showing our new design, the handle being shown with reference to a container shown in dashed lines to which the handle is attached;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.
